UNITED STATES PATENT OFFICE.

BENJAMIN W. TUCKER, OF SOUTH ORANGE, NEW JERSEY, ASSIGNOR TO CORONA
TYPEWRITER COMPANY, INC., A CORPORATION OF NEW YORK.

TYPE-WRITING MACHINE.

1,311,929.

Specification of Letters Patent.

Patented Aug. 5, 1919.

Application filed May 26, 1916. Serial No. 100,037.

To all whom it may concern:

Be it known that I, BENJAMIN W. TUCKER, a citizen of the United States, and a resident of South Orange, county of Essex, 5 and State of New Jersey, have invented certain new and useful Improvements in Type-Writing Machines, of which the following is a full, clear, and exact description.

This invention relates more particularly 10 to the carriages of typewriting machines in which work sheets wider than the carriage may be written upon.

One of the principal objects of the invention is to provide a carriage for a writing 15 machine, in which a platen may be mounted and which is so constructed that work sheets, as wide paper, long envelopes, and the like may be placed about the platen and the work sheet handled in as ready a manner 20 as in the ordinary machine, without making the carriage extensible and without in any way interfering with the proper working of the parts of the carriage or the parts usually associated therewith.

25 Another object of the invention is to provide a simple and efficient carriage in which the platen may be supported at its ends and the work sheet so held about the platen that the platen may be independently rotated or 30 moved for line spacing, notwithstanding the fact that the work sheet may extend on either or both sides beyond the ends of the platen.

Other objects of the invention are to provide 35 simple and efficient means whereby the work sheet may be released in order that it may be readily adjusted about the platen; to provide simple means for supporting the work sheet while being written upon; to provide 40 simple means whereby the work sheet may be released; and to provide simple and efficient line-spacing means for the platen.

A further object of the invention is to 45 provide a simple and efficient carriage adapted for visible writing, which may be readily made and assembled, and in which the parts need not necessarily occupy much more space than the ordinary carriage.

50 A still further object of the invention is to provide a carriage which is particularly adapted for small portable personal writing machines of various kinds.

With these and other objects in view, the invention will be hereinafter more particularly described with reference to the accompanying drawings, which form a part of this application, and will then be pointed out in the claims at the end of the description.

55 In the drawings, Figure 1 is a front elevation of one form of carriage embodying the invention.

60 Fig. 2 is an end elevation of the carriage looking from the left hand side of the machine.

65 Fig. 3 is an end elevation looking from the right hand side of the machine.

70 Fig. 4 is a view similar to Fig. 3, except that the feed roll and certain other parts have been moved to a position to release the work sheet about the platen.

75 Fig. 5 is a sectional view, partly in elevation, showing means for rotating the platen independently of the line-spacing means.

Fig. 6 is a fragmentary plan showing how 80 the pressure roll is mounted.

Fig. 7 is an enlarged fragmentary elevation showing a part of the line-spacing means.

85 Fig. 8 is a vertical section, partly in elevation, showing the line-spacing means in end elevation.

Fig. 9 is a front elevation looking in a direction opposite to that shown in Fig. 7.

Fig. 10 is a detail perspective view of the 85 line-spacing pawl.

Fig. 11 is a detail plan view of the means forming a stop for the pawl-carrying lever.

Fig. 12 is a detail perspective of the line-spacing stop for determining the extent of 90 line-spacing movement.

Fig. 13 is a vertical section, partly in elevation, showing a somewhat different construction including a different form of line-spacing means.

95 Fig. 14 is an end elevation of the carriage shown in Fig. 13.

Fig. 15 is a front elevation.

Fig. 16 is an end elevation looking in the direction opposite to that shown in Fig. 14.

100 Figs. 17 and 18 show a form of latch in a locked and a released position to adapt the platen to be directly rotated by an extensible stem or shaft.

105 Fig. 19 is a plan view of still another form of platen carriage.

Fig. 20 is an end view; and

Fig. 21 is a view similar to Fig. 20 except that the platen has been moved to release the work sheet from the pressure roll.

5 While the invention is shown as applied to carriages constructed to adapt work sheets of the usual or of widths wider than the carriage to be written upon, it will be understood that many of the features shown 10 may be employed in connection with carriages or writing machines of various kinds and constructions.

The carriage bed 10 may be supported in any desired way and mounted to travel 15 lengthwise of the bed under the force of a spring drum or other motor is a carriage 11. As shown the carriage is provided with rollers 12 along one edge thereof, and ball bearings 13 along the other edge so as to adapt 20 the carriage to move readily along its bed. The carriage is also adapted to be controlled by suitable escapement mechanism, but such mechanism as well as the mounting of the carriage may be of any suitable construction.

25 The carriage frame 14 has end pieces, brackets or frame members 15 which may be joined together by a member or work sheet receiver 16. The member 16 may be of open work, as wire, or thin plate, either solid 30 or provided with openings to lighten the same, and if made of metal, as aluminum, will add comparatively little weight to the carriage. The end members or brackets 15 are substantially annular in form, having an 35 opening, throat, or channel 17. The member 16 is substantially cylindrical in form, and is arranged to conform to the shape of the opening 18 of the end pieces 15. The ends of the cylindrical member 16 are not joined 40 together but provide a throat or opening corresponding to the channel 17 in order that the work sheet may be caused to pass through the opening 18 into and from the cylinder 16, as will be presently de- 45 scribed. One end of the member 16 is fastened to the end brackets 15 by screws or otherwise, and the other end of the cylindrical member 16 may be provided with up- 50 turned parts or lugs 20, by which said end 55 may be secured by screws 21 or otherwise to the outer surface of said brackets 15. The end brackets 15 are extended forward to provide lugs 22 and mounted in said lugs to rotate therein is a platen or roll 23. The 60 platen is supported at its ends in the brackets 15 and extends substantially throughout the entire distance between said end brackets 15, and is adapted to take the impact of the type in the usual way. A pressure roll 65 24 is arranged under the platen 23 and is normally held yieldingly against the platen to grip the work sheet when passed about said platen. The work sheet, if of some length, extends back of the platen and pressure or feed roll 24, and ascends through the

throat 17 into the opening 18, formed by the cylinder or body 16 wherein it may be rolled upon itself to occupy as little space as possible, and from which condition the said work sheet is fed forward between the feed 70 roll and platen upwardly above the platen as is usual in visible writing machines.

The pressure or feed roll 24 is held to rotate in a carriage frame member 25. This frame member is hinged at 26 to the forward ends 27 of the carriage end brackets 15. A rod 28 extends lengthwise of the carriage between the end frame brackets 15 forming a hinged connection between the part 25 and said end brackets. A transversely extending bar 29 is held at its ends between the end brackets 15 and a bar 30 extends between the ends of the carriage frame member 25 for the pressure roll. The two bars 29 and 30 are arranged in parallel 80 relation and have lugs 31 extending outwardly therefrom so as to provide bearings for the rod 28. At one or both ends of the rod 28 is arranged a spring 32 one end of which spring is held under the bar 29 and the other end under the bar 30, the tension of the spring or springs tending to force the frame 25 with the pressure roll 24 against the platen so that under normal conditions the platen and pressure roll will rotate in 95 unison. The carriage frame part 25 has a plate 33 on its upper surface which forms substantially a continuation of the forward edge of the member 16, and said plate with the plate like cylindrical member 16 provides a proper surface for guiding the work sheet backwardly or forwardly between the platen and pressure roll without offering any obstruction thereto whatever. The plate 33 is cut away to permit the roll 24 to extend through the same, and said roll 24 is also cut away to provide spaced members or parts 34 between which parts a part of the plate 33 extends in order that a substantially continuous table may be provided for the 105 work sheet. A handle 35 may be arranged at either or both sides of the machine on the pressure roll frame 25 to adapt said frame to be moved on its hinge 26 to release the pressure roll from the platen to adapt the 110 work sheet to be adjusted. By this means the work sheets may be properly held and fed between the platen 23 and the pressure roll 24, either into the body or receiver 16 or forwardly for printing purposes, as de- 120 sired.

A knob 36 is mounted to rotate upon a stud 37. This stud 37 is held to one of the carriage end brackets and may be located adjacent to the handle 35. The knob 36 125 may be held to a sleeve 38, and on the inner end of said sleeve is a pinion 39 which meshes with another pinion 40. The pinion 40 is held to the axis 41 of the pressure roll so that by rotating the knob the pressure roll 130

may be rotated in either direction for feeding the work sheet.

As a means for line-spacing the platen I provide a ratchet wheel 42 which is engaged by a lever-actuated pawl 43. The pawl 43 is mounted upon a manually operable lever 44. This lever is pivoted to swing about the shaft or stud 45, and during its swinging movement causes the pawl to move the ratchet wheel 42 according to the distance the lever 44 is moved, there being a spring 46 tending normally to force the pawl 43 into engagement with the teeth of said ratchet wheel. The shaft or stud 45 is mounted on one of the carriage end brackets at substantially a right angle to the axis of the pressure roll, and on the inner end of said shaft 45 is a bevel gear or pinion 47 which meshes with a smaller gear or pinion 48 on the axis of the pressure roll, so that when the ratchet wheel 42 is rotated a rotary movement is imparted to said pressure roll. The lever 44 moves in a direction lengthwise of the carriage, and may serve as a means for moving the carriage backward against its letter-spacing movement and with such backward movement simultaneously line-space the platen. The lever 44 has a downwardly projecting part 49 to which is held one end of a spring 50, said spring at its other end being secured to a fixed part of the carriage frame. The part 49 of the lever 44 is adapted to engage a stop 51. This stop is for the purpose of limiting the extent of movement of the lever 44 so that the platen may be moved a single or double space or otherwise, according to the position of said stop 51. This stop 51 is rotatably held on a stud 52. The stop 51 comprises a block portion or part 53, and formed integral with the block portion is a knurled head 54 by which the stop may be rotated, said head 51 being spaced from the block 53 by a reduced portion 55. The block 53 may be substantially rectangular in cross section and is normally held in different adjusted positions by means of a spring 56, one end of which is held to a fixed part of the carriage and the other end of which is free and is adapted to engage one of the sides of the block 53 to frictionally hold the same in any one of its adjusted positions. The block 53 is cut away to provide an engaging portion 57 on one side thereof, and is cut away at 58 to provide another engaging portion. The engaging portions 57 and 58 are of relatively different distances from the axis of the stop and as such engaging portions of the stop are the parts engaged by the projecting end 49 of the line spacing lever 44 the extent of movement of said line-spacing lever is determined by said portions. When the stop is adjusted so that the lever end 49 will engage the plane side of front of the block 53 a single

line-space movement may be imparted to the platen, and when the stop is adjusted so that the lever will engage the part 57 two line spaces may be given to the platen at a single movement of the lever 44, and if the stop is adjusted so that the lever end 49 engages the cut away part 58 the platen may be given three line-space movements. The line-spacing lever 44 may have its backward movement limited by a suitable stop 58. On the end bracket or a part projecting therefrom adjacent to the ratchet wheel 42 may be an enlarged cam portion 59 which is adapted to be engaged by the pawl 43 during its backward movement so as to release the pawl from engagement with the teeth of the ratchet wheel, when the lever 44 is in its normal position. A toothed wheel 60 is secured to the shaft of the pressure roll and this toothed wheel is adapted to be engaged by a roll 61. The roll 61 is carried upon an arm 62 and this arm is normally forced toward the toothed wheel 60 by a spring 63 and tends normally to hold the pressure roll in any one of its line-spacing movements and permits the said pressure roll to be moved in either direction.

The carriage may be provided with paper fingers 64 which are adjustably held to a bar 65 carried by the pressure roll frame 25. These fingers may be adjusted lengthwise of the platen and at the upper end thereof may have rolls 66 mounted thereon as is usual. The pressure roll frame 25 may be provided with a scale 67 at the forward edge thereof, and there may be also provided type-lining means, as 68, which may be hinged to adapt the same to be moved with the pressure roll away from the platen.

In Figs. 13 to 16 a construction is shown wherein the line-spacing mechanism is arranged upon the axis of the platen itself instead of the pressure roll, and means is also provided whereby the platen may be directly operated independent of the line-spacing mechanism. As shown the carriage 69 is constructed, except so far as the line-spacing means and the means for rotating the platen is concerned, substantially the same as already described. The pressure roll 70 is mounted upon a movable frame so as to be released from the platen 71 and the form of the carriage frame with the cylindrical receiver and the elongated throat for the work sheet is the same as that shown in Figs. 1 to 4. The platen 71 may have the usual roll member with the impact cylindrical covering of rubber or other material and at one end thereof may have a bushing 72 and at the other end may have a bushing 73.

The bushing 72 has a stem or stud portion 74 projecting outwardly from one side thereof, and this stem has a reduced part entering an opening in one of the carriage end

brackets to rotatably support the platen at one end in the carriage frame. The bushing 73 is provided with a central opening therethrough and extending through the opening 5 is a shaft or rod 75. The rod 75 extends through an opening in the carriage end frame adjacent to the bushing 73 some distance into the platen and at one end is provided with a knob or button 76. At the opposite end of the rod 75 within the platen is a key 77 which is adapted to engage a slot or key-way in a collar 78 forming a part of the platen. The key 77 permits the extension of the rod 75 so that said rod may be 10 made to rotate the platen whether the knob 76 is close to the end bracket of the carriage or at a distance therefrom. This permits the platen to be rotated manually at will in either direction independent of the line-spacing mechanism in case the work sheet is wider than the carriage is long. The rod 75 may be grooved at intervals as at 79, and adapted to engage said grooves is a latch 80. The latch 80 is pivoted at 81 to the carriage frame and is normally forced in one direction by a spring 82. The latch is provided with an opening 83 through which the rod 75 passes and said opening provides an engaging part 84 to enter the 20 groove to prevent the rod from being extended or forced into the platen and to hold the same in its adjusted position whatever it may be until the latch 80 is released. The latch 80 is substantially bell-crank in form 25 and on one arm thereof is provided with a finger-key or part 85 by which the latch may be depressed as shown in Fig. 17 to release the same from engagement with any one of the grooves 79 and thereby permit adjustment of the rod 75.

As line-spacing means for the construction shown in Figs. 13 to 16 the stem 74 of the bushing 72 is provided with a ratchet wheel 86. This ratchet wheel 86 is adapted 45 to be engaged by a pawl 87 which is pivotally held to a lever 88 and is normally pressed by a spring 89 into engagement with the teeth of the ratchet wheel. The lever 88 is pivotally held to the stem 74 and is 50 connected by a link 90 to a lever 91. The lever 91 is pivoted at 92 to one of the carriage brackets and has a finger portion 93 located at the rear of the carriage. The lever 91 is sickle-like in form, having the main 55 body portion thereof grooved to the shape of the cylindrical body of the carriage so as not to interfere with the work sheet when extending within the carriage as already explained. The lever 93 and pawl carrying 60 lever 88 may be restored to a normal position by a spring or otherwise, and the extent of movement of the lever 88 may be limited by a manually movable stop 94 in substantially the same manner as the line-spacing action of the pawl is controlled in 65

the Corona typewriter. The platen may also be held in its various suggested positions by a friction roll as 95, which is supported at the end of a spring held lever 96 and which serves to hold the platen and still 70 permit it to rotate in either direction.

Figs. 19 to 21 show a construction where in the platen itself may be raised to release the work sheet for adjustment or other purposes. In this form the carriage 97 has a cylindrical body 98 with a throat 99 for the passage of the work sheet, as already described, and has a forwardly extending part 100 in which is rotatably held a pressure roll 101. The pressure roll 101 is adapted to be rotated by a knob 102 and instead of being pressed against the platen as in the other form the platen 103 is pressed normally against the roll 101. As shown, the platen 103 is mounted to rotate in arms 104 at each end of the carriage, only one of said arms being shown. The arms 104 are pivoted at 105 to the forward part of the carriage frame adjacent to the throat 99 and said arms and platen are normally forced 85 toward the roll 101 by springs 106. The springs 106 may be arranged around a rod 107 having one end thereof engaging the arms 104 and the other end engaging under a fixed part of the carriage tending normally 90 to force the platen downwardly. A handle 108 may be arranged on one or both arms to adapt the platen to be raised to release the work sheet, as shown in Fig. 21. Except 95 as described, the parts shown are substantially the same as that shown in the other figures.

It will be evident from the foregoing that a carriage construction is provided whereby wide or long work sheets may be employed 105 and written upon which are wider than the length of the carriage or the platen; that simple means are provided whereby the work sheet is properly held between pressure means and the platen; that the construction is such that the carriage is adapted 110 for front strike or other writing means; and that simple and efficient means is provided whereby the work sheet may be readily adjusted and line spaced.

Having thus described my invention, I claim as new and desire to secure by Letters Patent:—

1. In a typewriting machine, the combination of a platen carriage, a tubular open-ended work sheet holder mounted on the carriage and formed with a throat extending throughout its length, a platen rotatably supported on the carriage adjacent said throat at the reverse side of the path of the work sheet, a pressure roll, yieldable means mounted on the carriage at the impression side of the path of the work sheet for supporting said roll and normally forcing the same against the platen, and line-spacing 120

115

125

130

135

140

mechanism operatively connected to rotate the pressure roll and mounted on said yieldable roll-supporting means at the impression side of the path of the work sheet.

- 5 2. In a typewriting machine, the combination of a platen carriage, a tubular open-ended work sheet holder mounted on the carriage and formed with a throat extending throughout its length, a platen rotatably supported on the carriage adjacent said throat at the reverse side of the path of the work sheet, a pressure roll, yieldable means mounted on the carriage at the impression side of the path of the work sheet for supporting said roll and normally forcing the same against the platen, line-spacing mechanism operatively connected to rotate the pressure roll and mounted on said yieldable roll-supporting means at the impression side of the path of the work sheet, and a finger wheel journaled on the roll-supporting means and operatively connected to rotate the pressure roll in either direction.
- 10 3. In a typewriting machine, the combination of a carriage, a tubular open-ended work sheet holder formed with a throat extending from end to end thereof, means for supporting said holder upon the carriage with its ends and the ends of the throat unobstructed, a platen rotatably supported on the carriage forwardly of the holder adjacent the upper side of said throat, a roll supported on the carriage below the platen adjacent the lower side of said throat and adapted to coöperate with the platen to feed a work sheet through the throat, means for guiding a work sheet upwardly over the front of the platen, a line-space lever located forwardly of the path of the work sheet, and connections between said lever and roll for rotating the roll located below the path of the work sheet.

- 15 4. In a typewriting machine the combination of a carriage having end brackets and a substantially cylindrical work sheet holder supported in said brackets, said end brackets and work sheet holder being formed with a longitudinally extending throat to adapt a work sheet to pass into and from the holder, a platen supported in the carriage end brackets forward of the holder, a frame pivotally held to the carriage end brackets, springs normally forcing the frame toward the platen, a pressure roll rotatably held in the frame and adapted to engage the under side of the platen, a knob located at one end of the carriage, an operative connection between the knob and the pressure roll for rotating the pressure roll, line spacing means for rotating the roll located at the opposite end of the carriage, and a line space lever for actuating said line spacing means located forwardly of the platen.

5. In a typewriting machine, the combination of a carriage having end brackets, a tubular work sheet holder mounted in said brackets and having unobstructed open ends, said end brackets and holder being formed with a throat having unobstructed open ends to adapt a work sheet of greater width than the carriage to be passed into and out of the tubular work sheet holder, a platen supported at its ends in the carriage end brackets, a frame pivotally held to the end brackets, a pressure roll rotatably mounted in the frame, yieldable means for forcing the pressure roll against the platen, and means located at the impression side of the path of the work sheet for actuating the platen and pressure roll to feed the work sheet.

6. In a typewriting machine the combination of a carriage having end brackets of substantially annular form, a substantially cylindrical work sheet holder supported at its ends in said brackets and having unobstructed open ends, said end brackets and holder being formed with a throat having unobstructed open ends to adapt a work sheet of greater width than the carriage to be passed into and out of the cylindrical holder, a platen rotatably supported at its ends in said brackets, a roll coöperating with the platen to move a work sheet through the throat into and out of the holder, and line spacing mechanism operable from the front of the machine irrespective of the width of the work sheet.

7. In a typewriting machine, the combination of a carriage having end brackets of substantially annular form, a substantially cylindrical work sheet holder supported at its ends in said brackets and having unobstructed open ends, said end brackets and holder being slotted to form a throat having open ends, a platen rotatably supported at its ends in said brackets forwardly of the holder, a roll located below the platen and adapted to coöperate with the platen to feed a work sheet through the throat of said holder, means for guiding a work sheet between the platen and roll and upwardly about the platen, yieldable means held to the carriage end brackets below the path of the work sheet for supporting said roll, and means located at the impression side of the path of the work sheet for rotating the roll.

8. In a typewriting machine, the combination of a carriage, an open-ended work sheet holder mounted on the carriage and formed with a discharge throat extending throughout the length thereof, a platen supported on the carriage forwardly of the holder at the reverse side of the path of the work sheet, a roll supported on the carriage at the impression side of the path of the

work sheet and adapted to coöperate with the platen to feed a work sheet through the throat of said holder, line-spacing mechanism supported on the carriage at the im-
5 pression side of the path of the work sheet and adapted to rotate said roll, and a finger wheel journaled on the carriage at the im-

pression side of the path of the work sheet and operatively connected to rotate the pres-
sure roll in either direction.
